L. C. HISEY

SAFETY COUPLING

Filed Oct. 6, 1924

UNITED STATES PATENT OFFICE.

LYMAN C. HISEY, OF LOS ANGELES, CALIFORNIA.

SAFETY COUPLING.

Application filed October 6, 1924. Serial No. 741,908.

This invention relates to safety devices to be used in connection with drilling oil wells and pertains more particularly to a safety coupling for drill pipe and the like.

5 The principal object of this invention is to reduce or to practically eliminate the loss of time caused by so-called "twist-offs."

It will be understood, in consideration of this invention, that a twist-off, practically speaking, is caused by parting of the drill pipe, and the result is that that part of the drill pipe below the point of parting cannot be withdrawn from the hole except by the application of fishing tools. The usual time lost is that required for the removal of the upper portion of the drill pipe and the successive attempts to fish out the said lost portions.

20 In the great majority of cases, drill pipe will part at or adjacent to the lower threaded portion of the pipe section where it screws onto a tool joint. It is a particular object of this invention to provide means whereby those portions of the drill pipe below the twist-off may be removed along with the portions above the twist-off.

Another object of the invention is to provide a comparatively inexpensive safety coupling so that any operator can afford 25 to install one at each and every tool joint throughout the string of pipe so that no matter where a twist-off occurs the entire string of pipe may be removed as readily as though no twist-off had occurred.

30 Still another object of the invention is to provide a device of the character described which will not come into operation until an attempt is made to actually raise the pipe.

40 A further object of the invention is to provide a device of the character described which will not be affected should the drill pipe continue to rotate for any appreciable time after the twist-off occurs.

45 Still other objects and advantages will appear hereinafter.

I have illustrated by the accompanying drawings one practical embodiment of my invention.

50 In the said drawings,

Figure 1 is a view in vertical section of the said embodiment as applied to a tool joint and adjacent sections of drill pipe;

55 Figure 2 is a view in section thereof seen on the line 2-2 of Figure 1;

Figure 3 is a view in section seen on the line 3-3 of Figure 1;

Figure 4 is a view in vertical section similar to that of Figure 1, showing the device in operation; Figure 5 is a view in vertical section of a part of the device hereinafter known as the friction means, as it appears in normal expanded position apart from the drill pipe.

More specifically, 7 and 8, respectively, 65 indicate sections of drill pipe which are connected to each other by tool joint members 9 and 10, such arrangement of pipe sections and tool joints being that most commonly employed. In carrying out my invention, 70 section 10 of the tool joint is internally threaded as at 11 to receive the improved safety coupling which will now be described.

The coupling includes a mandrel 12 of 75 tubular form to provide a bore or fluid course 14, so that circulation through the bore 15 of the drill pipe is not interfered with.

The mandrel is provided with elongated 80 apertures, such as 16, to allow mud to easily enter or leave the bore of the mandrel and to prevent clogging of the ends thereof. Said mandrel is externally threaded at the lower end, as at 18, so that it may be attached to the corresponding section of the tool joint. It is found from experience that in about 80% of the twist-offs the pipe parts at about the point generally indicated by the numeral 20.

85 My improved coupling further includes a friction member 21 arranged to frictionally engage the inner margin 22 of the upset end of the drill pipe. In the embodiment illustrated, said friction member is composed of 90 spaced rings 24 and 25 which are a loose sliding fit upon the mandrel and which are connected by a plurality of bowed flat springs 26. The friction member is shown in Figure 5 as it appears when allowed to 95 assume normal shape. When a drill pipe or tubing section is forced over this friction member, particularly when the friction member is in position over the mandrel, the parts will assume the position shown in Figure 1 and the springs will frictionally engage the inner margins of the pipe over which it is fitted. The upper end of the mandrel is externally tapered as at 27, so 100 that it increases in diameter upwardly. 105

110

A plurality of slips 29 are provided which are equally spaced circumferentially about the tapered part of the mandrel. Said slips are held in sliding engagement with the 5 tapered surface by means of a flat spring member 30 which comprises about one and one-half or more convolutions. When said spring is formed and tempered, its normal diameter is slightly less than the diameter 10 which it assumes when it is caused to encompass the assembly of the slips and the mandrel.

Obviously, if the slips and the spring are forced upward as a unit along the tapered 15 surface, the outer toothed surfaces 31 of the said slips will be gradually moved toward the inner margin of the pipe, and the assembly of slips and coil spring will increase in effective circumference.

20 In taking advantage of my invention, in the operation or in the use of drill pipe, tubing and the like, the complete device, including mandrel, slips and friction member, should be installed as shown in Figure 1, 25 at each tool joint. To install the safety coupling, it is only necessary to screw the mandrel with the attached friction means and slips to the upper tool joint member. To attach the tool joint member to the pipe 30 section, it is only necessary to force the friction means and mandrel into the open end of the pipe before the actual operation of securing the tool joint to that end of the pipe is accomplished. Once the tool joint 35 member is so attached to the pipe, such operation does not have to be repeated, and in disconnecting stands of pipe at the tool joints the couplings are not interfered with or exposed. In fact, my improved safety 40 couplings do not in any way increase the time required to withdraw the pipe from the well. The couplings once installed may be left in place indefinitely and require no attention nor inspection.

45 Assuming that a twist-off occurs at any point between the upper section of the tool joint and that part of the pipe wall which is engaged by the friction member, the operation of the device will be as follows.

50 Should the pipe part at such point, that portion of the drill pipe above the point of twist-off will probably continue to rotate or be rotated until such time as the driller becomes aware of the twist-off and brings the 55 rotating means to a stop. During such unnecessary rotation of the drill pipe, the friction means with its collars is quite free to revolve upon a mandrel and produces no effect whatsoever in so far as operation of 60 the device is concerned.

65 Due to the suddenly decreased load or torque, the driller is aware that a twist-off has occurred, and after having stopped the rotating means may start to hoist the pipe.

65 Now, when the pipe is being hoisted that

portion below the twist-off will tend to remain stationary in the bore of the well. Therefore, it may be said that the pipe above the twist-off, together with the friction means and its collars, will move upward 70 relative to the tool joint.

When the friction means and its collars are moved upward relative to the tool joint, said collars, of course, move upwardly relative to the mandrel. As a consequence, a 75 plurality of slips are jointly moved upward along the mandrel by virtue of the frictional engagement of the springs with the inner margin of the pipe. By the time the slips have been so moved a few inches, their toothed outer surfaces will be brought into 80 contact with the inner margins of the wall and will effectively engage same, whereupon there is a tendency for the slips to be moved even further upward. Therefore, immediately 85 after the toothed surfaces come in contact with said margins, a combined frictional engagement and wedging action will be set up between such surfaces and margins, and that portion of the drill pipe above the 90 twist-off will become most effectively attached indirectly to the mandrel.

It will be apparent, now, that as the pipe above the twist-off is hoisted, all portions of the pipe below the twist-off will be hoisted, 95 the mandrel acting as the connecting link. Therefore, by installing my improved safety coupling in each tool joint, the only delay that will be occasioned by a twist-off is the time required to hoist the pipe, replace 100 the broken sections, and again lower the entire string into the hole. Should the twist-off occur at or near the time when a change of bits is contemplated, no appreciable loss 105 of time will be experienced.

While I have shown and described a specific embodiment of my invention, I do not limit myself to any specific construction or arrangement of parts, and may alter the construction and arrangement of parts as 110 occasion may require without enlarging the scope of the invention within the appended claims.

I claim as my invention:

1. In combination, pipe sections, a joint 115 connecting said sections, a mandrel carried by said joint and extending into the interior of one pipe section, and expanding means carried by said mandrel arranged to expand and connect with the pipe should 120 said pipe move relative to said joint.

2. In combination, pipe sections, a joint connecting said sections, a mandrel carried by said joint and extending into the interior of one pipe section, and expanding 125 means carried by said mandrel arranged to expand and engage said pipe internally should said pipe move relative to said joint.

3. In combination, expanding pipe engag- 130 ing means adapted to engage the inner mar-

gin of a pipe should the pipe be moved in a given direction relative to said means, and a tool joint to which the pipe and pipe engaging means may be each secured with the 5 said means internally of the pipe.

4. In combination, a pipe, a tool joint carried by said pipe, a mandrel carried by said tool joint and extending into the bore of said pipe, expanding means carried by said 10 mandrel for engaging the inner surface of the pipe in event said pipe is moved longitudinally and relative to said joint and means carried by said mandrel frictionally engaging the inside of the pipe constantly 15 and operative to expand said means upon such movement.

5. In a device of the character described, a mandrel having a portion of increasing diameter upwardly, pipe engaging slips assembled around said mandrel and movable along the mandrel vertically, a collar loosely 20 encompassing said mandrel below the slips,

and friction means frictionally engaging said pipe internally, said means arranged to move said collar with itself. 25

6. In combination, a pipe, a tool joint at the lower end of the pipe, a mandrel carried by said joint and extending upwardly into the bore of said pipe, and wedging means carried between said mandrel and 30 pipe arranged to connect the mandrel to the pipe when the latter moves upwardly relative to the former.

7. In combination, a pipe, a coupling screw threaded to one end of said pipe, a 35 mandrel attached to said coupling and extending into said pipe, expanding pipe engaging means carried by said mandrel, and means frictionally connecting said pipe and 40 said pipe engaging means whereby said expanding means is caused to expand after a predetermined longitudinal movement of said pipe to said coupling.

LYMAN C. HISEY.
